(57) **CLAIM**

The ornamental design for a radar array, as shown and described.

DESCRIPTION

FIG. 1 is a perspective view of a radar array according to the present invention;

FIG. 2 is a rear elevational view thereof;

FIG. 3 is a front elevational view thereof;

FIG. 4 is a top plan view thereof;

FIG. 5 is a bottom plan view thereof;

FIG. 6 is a left side elevational view thereof; and,

FIG. 7 is a rear elevational view thereof.

Reference being had to the accompanying drawing, forming a part hereof, those portions shown in dashed lines for illustrative purposes only and forming no part of the claimed design.

1 Claim, 3 Drawing Sheets

FIG. 1.

FIG. 6.

FIG. 7.

FIG. 3.
